UNITED STATES PATENT OFFICE

125,885

DESIGN FOR A WATCHCASE

Julius Dinhofer, New York, N. Y.

Application December 11, 1940, Serial No. 97,249

Term of patent 7 years

To all whom it may concern:

Be it known that I, Julius Dinhofer, a citizen of the United States and a resident of the city, county, and State of New York, have invented a new, original, and ornamental Design for Watch Cases, of which the following is a specification, reference being had to the accompanying drawing, forming a part thereof, in which

Fig. 1 is a top plan view of a watch case showing my new design, the essential features of which reside in the parts shown in full lines, and Fig. 2 is a side elevational view of the same.

I claim:

The ornamental design for a watch case, substantially as shown and described.

JULIUS DINHOFER.
